CONTROL MEANS FOR PUSHER ELEMENTS
OF ROLLING MILL SKID BEDS

Matthias Langen, Parkstone, England, assignor
to The Loewy Engineering Company Limited,
London, England, a corporation of Great
Britain

Application October 14, 1943, Serial No. 506,184
In Great Britain October 15, 1942

7 Claims.

(Cl. 80—48)

This invention relates to control means for carriage-mounted pusher elements which serve to transport billets, bars, rods or other articles across the skid-bed of a rolling mill installation or from or onto a roller table or other conveyor means, and it relates in particular to that type of pusher element which was pivotally supported in the carriage, a pair of abutments being provided therein by means of which the pusher element could be prevented from swinging in either direction when in contact with one of the abutments. By disengaging the pusher element from contact with one abutment and establishing at the same time contact with the other abutment, the direction of carriage movement in which the pusher element could act as a transport means was reversed.

The above arrangement enabled the pusher elements, when meeting a billet, bar or other article on their advance in one direction, to shift such article across the skid-bed or from or onto a roller table, as the case might be. On their advance in the opposite direction, however, the pusher elements would be tilted over into an ineffective position below the skid-bed by any article supported thereon, but as soon as the pusher elements had passed underneath that article, they would swing back and resume their upright position, by means of a counterweight.

In a more specific type of pusher element, change of the position of its pivotal support within its carriage, and thereby change of the abutment contacts, was effected automatically at pre-selected points of the carriage travel by means of rotary cams mounted on a shaft in the carriage and co-operating with stops positioned in the path of the carriage.

In the above-mentioned known type of pusher element, engagement of the cams with their stops could be maintained during the beginning of the cam-shaft rotation only, whilst the remainder of the rotation had to be carried out without positive control and solely under the influence of the momentum gathered during the comparatively short period of positive control. This was not a very reliable method of operation. Sufficient momentum could only be acquired if the cams were made to impinge on their respective stops with considerable force, and the consequent violent impact resulted in rapid wear, and sometimes breakage, of the components of the carriage. When the momentum was insufficient, the cam-shaft would stop half-way in its rotation and the pusher element mounted on that cam-shaft would not take up its effective po-

sition. Such incidents were liable to interfere considerably with the smooth working of the transport and the flow of material through the plant.

5 The invention refers in particular to a construction of this type wherein the pusher elements were loosely mounted on crankpins and the cams were mounted on the crankshaft so that a change of position of the pusher element 10 in the carriage was brought about by a rotation of the crankshaft. The invention is, however, equally applicable to other forms of pusher elements.

The invention has for its object the provision 15 of an improved control means for carriage-mounted pusher elements for rolling mill skid-beds, free from these drawbacks and with additional advantageous features.

It is a more specific object of the invention to 20 provide control means for a pusher element of the type described which is positive-acting throughout its movement.

It is a still further object of the invention to provide control means which can be arranged at 25 any point along the path of the carriages and which can be selectively brought into play in accordance with requirements.

Further, by providing additional abutments in 30 a carriage and by omitting others, it is possible for a pusher element to be prevented from, or to be set free for, swinging over in both directions of rotation by changing its position in the carriage, the change-over from one position to another being effected, as before, by rotation of 35 the cam-shaft, and it is an object of the invention to provide control means which can be used irrespective of the arrangement of the abutments.

The invention will be described in detail by 40 way of example with reference to the accompanying drawings, in which:

Figs. 1 and 2 are a side elevation and plan view respectively of a carriage with a pusher element mounted therein and adapted to be operated by control means according to the invention, the guideways for the carriage and other details of the skid-bed being omitted here for the sake of clarity.

Fig. 3 is a vertical transverse section through 45 the carriage along the line 3—3 of Fig. 1, showing also the guideways of the carriage and a set of stops for the reversal of the pusher element.

Figs. 4 and 5 show in a more diagrammatical way the relative arrangement of these stops and 55 the cams co-acting therewith, Fig. 4 being a sec-

tion seen in the direction of the line 4-4 of Fig. 3, and Fig. 5 being a section seen in the direction of the line 5-5 of Fig. 3.

Fig. 6 is a cross-sectional elevation of a skid-bed having carriage-mounted pusher elements which are operated by control means according to the invention, the figure showing also a mechanism for simultaneously operating a plurality of stops arranged at corresponding points on a series of carriage guideways.

Figs. 7a and 7b show the two positions of a pusher element in a carriage having abutments which enable the pusher element to transport material in both directions—one direction for each position.

Figs. 8a and 8b show the two positions of a pusher element in a carriage having an abutment at one side of the pusher element only, so that the latter will transport material in one direction when in one position, and not when in the other position.

Figs. 9a and 9b show the two positions of a pusher element in a carriage having two abutments at one side and none at the other, so that the pusher element will transport material in both directions when in one position and not when in the other position.

Fig. 10 is a diagram illustrating various working positions, A, B, C, D, E, F and G, of a carriage and pusher element relative to a skid-bed and to billets being transported across the skid-bed.

Referring first to Figs. 1, 2 and 3, 10 is a carriage which is adapted to be moved in opposite directions along guideways 11 of a skid-bed by means of ropes 12 or the like attached to the ends of the carriage. The skid-bed will comprise a plurality of such carriages adapted to be moved along in unison in parallel guideways 11.

Supported in bearings 13 located in the carriage side-plates is a crankshaft 14. The crankshaft has a crankpin 15 on which pusher element 16 is loosely mounted. Each pusher element consists of a finger 17 and a counterweight 18 which tends to keep the finger in the upright position in which it projects above the material-supporting surface of the skid-bed so as to be effective as a transport means. Abutments 19 and 20 are provided at suitable places in the carriage to prevent the pusher element 16 from tilting over. Each abutment is adapted to co-operate with one of the faces 21 or 22 provided on the sides of the counterweight 18.

As shown more clearly in Figs. 7a and 7b, the pusher element 16 is prevented from tilting to the left when abutment 19 is in contact with face 21 and thus made effective for transport towards the right, and it is prevented from tilting to the right when abutment 20 is in contact with face 22 and thus made effective for transport towards the left.

To change over the pusher element 16 from one position to the other, it is merely necessary to rotate crankshaft 14 about 180°. This rotation is effected automatically at pre-selected points in the path of the carriage 10 by means of stops 23 and 24 which are adapted to co-operate with cams 25 and 26 arranged at opposite ends of the crankshaft 14, in a manner to be presently described and with reference to Figs. 3, 4 and 5.

Stop 23 can be retracted through an opening in the guideway 11 into an idle position outside the path of the carriage 10 as shown in Fig. 3. To this end, the stop 23 is mounted at the end of an arm 27 which is pivotally mounted on a

pin 28. Arm 27 has an extension 29 to which a pull-rod 30, or any other actuating mechanism, is attached.

As can be seen in Fig. 6, all the stops 23 which are arranged at corresponding points of parallel guideways can be actuated simultaneously by a common pull-rod 30. Movement of pull-rod 30 can be by means of a crank mechanism, part of which is shown at 31 and which is driven by a motor 32 or by any other suitable means. The pull-rod 30 and motor 32 or any other suitable means for retracting the stops 23 can be operated by remote control.

Stop 24 is fixedly secured to guideway 11 by means of a bolt 33 or the like.

Both stops 23 and 24 have oppositely inclined lateral faces and horizontal tops over which the cams 25 and 26 will wipe when coming into action. The stop 23 is slightly larger than the stop 24.

Cam 25 which co-operates with the retractable stop 23 is in the shape of a rectangular block centrally supported on crankshaft 14 so that it can be said to consist of two arms 25a and 25b (Fig. 4) arranged diametrically opposite the crankshaft axis. Cam 26 extends to one side of the crankshaft only and is curved symmetrically with respect to its radial axis (Fig. 5). Both cams are so mounted on the crankshaft that their radial axes form a right-angle, the normal position being that in which the axis of cam 25 is vertical, and that of cam 26 horizontal.

When carriage 10 is moved along its guideways 11, and assuming further that retractable stop 23 is in its forward position in which it projects into the path of the carriage, the lower arm 25a of cam 25 will strike against one of the inclined lateral faces of stop 23. Crankshaft 14 is hereby rotated by 90°, whereby cam 25 assumes a horizontal position and cam 26 is moved in a vertical downward position as shown by broken lines in Fig. 5. In its latter position, cam 26 is ready to be engaged on further movement of carriage 10 by one of the inclined lateral faces of stop 24, whereby crankshaft 14 will be rotated by another 90°.

At the end of this rotation, cam 25 will be again in a vertical position and cam 26 in a horizontal position, with the difference that the tip of cam 26 points in the opposite direction to that in which it pointed before.

Rotation of crankshaft 14 by 180° is now complete, and contact with counterweight 18 has been transferred from abutment 19 to abutment 20 and the direction in which the pusher element 16 is effective as a transport means has been reversed. During all this time, the finger 17 has been held in its upright position due to the action of counterweight 18 (see Figs. 7a and 7b).

Rotation of crankshaft 14 in the opposite direction and transfer of contact from abutment 20 back to abutment 19 is effected in a manner similar to that previously described when the carriage 10 is moved in the opposite direction, with the only difference that in this case opposite lateral faces of stops 23 and 24 and of cam 26 and the other arm 25b of block-shaped cam 25 will come into mutual engagement.

As will be seen from the foregoing, the crankshaft 14 will be under continuous positive control throughout its rotation, due to the successive co-operation between stops 23 and 24 with cams 25 and 26 respectively. It is further to be noted that one and the same set of stops and cams is used for rotation in opposite directions.

Should the operator inadvertently move the carriage 10 in a wrong direction, the block-shaped cam 25 will come in contact with the inclined surface of its corresponding retractable stop 23 and thus push that stop aside into the ineffective position shown in Fig. 6, whereby damage to the parts of the carriage control is avoided.

Owing to the disappearing feature of the stop which acts during the first part of the crank-shaft rotation, it is possible to arrange stops at any point along the path of the carriage whenever reversal of the direction of transport might be required at one time or another. A skid-bed with the control means according to the invention can, therefore, be easily adapted to a great variety of different transport conditions.

Another important feature of the invention is that the retractable stop can be operated by remote control, which makes it possible to install these control means at the general control pulpit of the mill.

Whilst Figs. 7a and 7b show how the invention can be applied to a carriage which has an abutment at each side of the crankshaft axis, each abutment preventing the pusher element from tilting over in one of two opposite directions, Figs. 8a and 8b and 9a and 9b show the application of the invention to carriages on which the abutments are distributed somewhat differently.

Figs. 8a and 8b show a carriage wherein an abutment is provided at the right side of the crankshaft axis only, so that the pusher element 16 will be prevented from tilting over to the left when at this side, but will be free to tilt over in both directions when shifted to the left side of the crankshaft axis.

Figs. 9a and 9b show a carriage in which an additional abutment 120 is arranged at the right side of the crankshaft axis which abutment is adapted to co-operate with a lug 121 projecting at the right side of the pusher element. The left side of the crankshaft axis is free from abutments, the same as in the case of the carriage according to Figs. 8a and 8b. When the pusher element of Fig. 9a is in its right position it will be prevented from tilting over in both directions by the combined action of abutments 20 and 120; when the pusher element is moved to the left position it will be free to be tilted over in both directions (Fig. 9b).

Reversal of the pusher element of the carriages shown in Figs. 8a and 8b and 9a and 9b can be effected by the same control means, consisting of stops 23 and 24 and cams 25 and 26, as in the case of carriages such as are shown in Figs. 7a and 7b which have one abutment each at either side of the crankshaft axis.

What I claim is:

1. A rolling mill skid-bed having a plurality of carriages movable in unison in parallel guideways, means for moving said carriages in opposite directions, each carriage containing a pusher element, a pivotal support for said pusher element, and control means for displacing said pivotal support from one position to another inside said carriage, said control means comprising a rotary shaft mounted in said carriage and connected with said pivotal support so that a rotary movement of said shaft will cause the displacement of said pivotal support, cams on said shaft adapted to come successively into action to cause such a rotary movement, each cam turning said shaft through a portion of the rotary movement required for the displacement of said

pivotal support, and stops arranged in the path of the carriage, each stop co-operating with one of said cams.

2. A rolling mill skid-bed having a plurality of carriages movable in unison in parallel guideways, means for moving said carriages in opposite directions, each carriage containing a pusher element for shifting material across said skid-bed, a pivotal support for said pusher element adapted to take up one of two different positions inside said carriage whereby the manner in which the pusher element is effective as a transport means is altered, and control means for displacing said pusher element from one position to another, said control means comprising a rotary shaft in said carriage connected with said pivotal support so that rotation of said shaft through a pre-determined angle will cause the pivotal support to be displaced from one position to the other, two cams on said shaft adapted to come successively into action, each cam turning said shaft through a portion of its aforesaid rotation, and two stops arranged in the path of the carriage to actuate said cams successively, each stop co-operating with one of said cams.

3. A rolling mill skid-bed having a plurality of carriages movable in unison in parallel guideways, means for moving said carriages in opposite directions, each carriage containing a pusher element for shifting material across said skid-bed, a pivotal support for said pusher element adapted to take up two different positions inside said carriage, and control means for displacing said pivotal support from one position to another, said control means comprising a rotary shaft in the carriage connected with the pivotal support so that rotation of said shaft through a pre-determined angle in opposite directions will cause the pivotal support to be moved from one position to another or back, cams on said shaft adapted to come successively into action, and stops arranged in the path of the carriage co-operating with said cams to actuate the same successively, said cams and said stops being of symmetrical shape so that they can rotate said shaft in opposite directions.

4. A rolling mill skid-bed having a plurality of carriages movable in unison in parallel guideways, means for moving said carriages in opposite directions, each carriage containing a pusher element for shifting material across said skid-bed, a pivotal support for said pusher element adapted to take up one of two different positions inside said carriage whereby the manner in which the pusher element is effective as a transport means is altered, and control means for displacing said pusher element from one position to another, said control means comprising a rotary shaft in said carriage connected with said pivotal support so that rotation of said shaft through a pre-determined angle will cause the pivotal support to be displaced from one position to the other, two cams on said shaft adapted to come successively into action, each cam turning said shaft through a portion of its aforesaid rotation, and two stops arranged in the path of the carriage to actuate said cams successively, each stop co-operating with one of said cams, the two cams being so arranged on said shaft that their radial axes form a right-angle.

5. A rolling mill skid-bed having a plurality of carriages movable in unison in parallel guideways, means for moving said carriages in opposite directions, each carriage containing a pusher element for shifting material across said skid-

bed, a pivotal support for said pusher element adapted to take up one of two different positions inside said carriage whereby the manner in which the pusher element is effective as a transport means is altered, and control means for displacing said pusher element from one position to another, said control means comprising a rotary shaft in said carriage connected with said pivotal support so that rotation of said shaft through a predetermined angle will cause the pivotal support to be displaced from one position to the other, two cams on said shaft adapted to come successively into action, each cam turning said shaft through a portion of its rotary movement, two stops arranged in the path of the carriage, each stop co-operating with one of said cams, and remote controlled means for retracting the stop which is adapted to come first into action.

6. A rolling mill skid-bed having a plurality of carriages movable in unison in parallel guideways, means for moving said carriages in opposite directions, each carriage containing a pusher element for shifting material across said skid-bed, a pivotal support for said pusher element adapted to take up one of two different positions inside said carriage whereby the manner in which the pusher element is effective as a transport means is altered, and control means for displacing said pusher element from one position to another, said control means comprising a rotary shaft in said carriage connected with said pivotal support so that rotation of said shaft through

a predetermined angle will cause the pivotal support to be displaced from one position to the other, two cams on said shaft adapted to come successively into action, each cam turning said shaft through a portion of its rotary movement, two stops arranged in the path of the carriage, each stop co-operating with one of said cams, and remote controlled means for retracting the stop which is adapted to come first into action.

- 10 7. A rolling mill skid-bed having a plurality of carriages movable in unison in parallel guideways, means for moving said carriages in opposite directions, each carriage containing a pusher element pivotally supported in its carriage, a pair of abutments adapted to make contact selectively with said pusher element so as to prevent the latter from tilting over, whereby it is made capable of acting as a transport means in one direction of carriage-movement, and control means for transferring the contact-making position of the pusher element from one abutment to the other, whereby the direction in which the pusher element is effective as a transport means is reversed, said control means comprising a number of cams rotatably mounted in said carriages and an equal number of stops at pre-selected points of the carriage path for co-operation with said cams, said cams and said stops being so arranged that they come successively into operation to shift the pusher element positively through successive portions of its movement from one abutment to the other.

MATTHIAS LANGEN.
